(57) **CLAIM**

The ornamental design for a golf hole illumination device, as shown and described.

DESCRIPTION

FIG. 1 is a perspective view of a golf hole illumination device showing the claimed design in accordance with a first embodiment;

FIG. 2 is a left-side elevational view thereof, a right-side elevational view thereof being a mirror image of the left-side elevational view;

FIG. 3 is a front elevational view thereof;

FIG. 4 is a back elevational view thereof;

FIG. 5 is a top plan view thereof;

FIG. 6 is a bottom plan view thereof;

FIG. 7 is a perspective view of the golf hole illumination device in accordance with a second embodiment;

FIG. 8 is a left-side elevational view thereof, a right-side elevational view thereof being a mirror image of the left-side elevational view;

FIG. 9 is a front elevational view thereof;

FIG. 10 is a back elevational view thereof;

FIG. 11 is a top plan view thereof; and,

FIG. 12 is a bottom plan view thereof.

Broken lines in the figures show portions of the golf hole illumination device that form no part of the claimed design.

1 Claim, 12 Drawing Sheets
